ABSTRACT

An electronic musical instrument including tone generators for generating tone signals each having predetermined tone pitches constituting a musical scale and tone keyers for respectively keying the tone signals, is further provided with a circuit arrangement for fluctuating the pitch of the tone at the start of the tone. The arrangement comprises a detector for detecting the start of the tone signal being played and a pulse generator producing a pulse signal upon receipt of the detected signal and controlling the tone generators to fluctuate the pitches thereof at the start of the tone signals. This simulates the sound of natural musical instruments very closely.

SHEET 2 OF 3

FIG. 2

FIG. 3

FIG. 4

**ELECTRONIC MUSICAL INSTRUMENT HAVING
TONE START PITCH FLUCTUATION
ARRANGEMENT**

BACKGROUND OF THE INVENTION

The present invention relates to an electronic musical instrument, and more particularly to an electronic musical instrument wherein the tone pitches are shortly fluctuated at the start of the tone signals.

Conventional musical instruments such as stringed, wind and percussion instruments generally produce sounds having such pitch or frequency that are not maintained at any predetermined pitch from the start to the decaying end of sounds, but are fluctuated higher or lower (usually, by about 20 to 30 cents) for a short time mainly at the start of the sound and then comes to its predetermined pitch during the sustaining or decaying period.

Electronic musical instruments, such as an electronic organ, are so designed as to generate tone signals having individually predetermined pitches by means of tone generators, and generally include a plurality (mostly, 12 constituting the highest one octave) of master oscillators and multistaged frequency dividers cascade connected in turn to each of the oscillators.

Accordingly, prior art electronic musical instruments have the disadvantages that they generate only monotonous tone signals each being maintained at its predetermined pitch from the rise to the decay thereof and widely departing from the sense of sounding of natural musical instruments.

Therefore, the principal object of the invention is to provide an electronic musical instrument having sounding characteristics closely resembling those of the sounds of natural musical instruments.

SUMMARY OF THE INVENTION

According to the present invention, there is provided an electronic musical instrument comprising tone generators generating tone signals, tone keyers connected to the tone generators and keying the tone signals, a tone signal passage or coupling means connected to the tone keyers and conducting the keyed tone signal, a detector connected to the tone signal passage and detecting a start of the keyed tone signal, and a pulse generator connected to the detector for producing a pulse signal upon detection of the tone signal start and to the tone generators for fluctuating the frequencies of the generating tone signals.

BRIEF DESCRIPTION OF THE DRAWINGS

FIG. 1 is a schematic block diagram of an electronic musical instrument according to an embodiment of the invention;

FIG. 2 shows a concrete circuit arrangement of the pulse generator of FIG. 1;

FIG. 3 illustrates a concrete circuit diagram of a part of the master oscillators and frequency dividers of FIG. 1; and

FIG. 4 is a schematic block diagram of an electronic musical instrument according another embodiment of the invention.

**PREFERRED EMBODIMENTS OF THE
INVENTION**

Referring now to FIG. 1, an electronic musical instrument according to an preferred embodiment of the invention is shown by numeral 10 as a whole.

The instrument 10 comprises a keyboard 12 having a plurality of keys 111, 112 . . . 11n juxtaposed in the order of musical notes; tone keyers 13 having a plurality of key switches provided for the respective keys 111 to 11n on the keyboard 12 to be actuated interlocking with the corresponding keys upon their selective depression; and tone generators 14 generating tone signals having pitches predetermined for the individual musical notes and, only upon depression of the corresponding keys, producing tone signals therefrom. The tone generators 14 include a plurality (generally 12) of master oscillators 15 for generating individually the tone signals in the highest octave and a plurality of multistaged frequency dividers 16 cascade connected in turn to each of the oscillators 15. The line 24 and the succeeding circuits 20, 21 and 22 constitute a tone signal passage or tone signal coupling means of the instrument.

With an electronic musical instrument arranged as described above, there is generated only monotonous tone signals each being maintained at a predetermined pitch from the start (rise) to the end (decay) thereof and widely departing from the sounding characteristics of natural musical instruments as well known in the art and as abovementioned.

Therefore, the instrument 10 of this invention has the following arrangement for tone start pitch fluctuation, in order to obtain tone signals having sounding characteristics as closely resembling those of the natural musical instruments as possible.

There is first supplied each tone signal generated by the tone generators 14 and derived through the tone keyers 13 and the line 24 to an amplitude limiter 17 consisting of, for example, a conventional saturation amplifier, and followed by a rectifier 18. The rectified signal from the rectifier 18 is then supplied as a trigger signal to a pulse generator 19 constituted by, e.g., a one-shot multivibrator 191 including two emitter grounded transistors TR₁ and TR₂ as shown in FIG. 2. The pulse generator 19 is so arranged as to be triggered by the trigger signal thus obtained and to generate a pulse signal e₁ having a relatively short duration time (e.g., about 20 ms) at the very moment of the starting portion of the keyed tone signal. This pulse width is determined by the values of a capacitor C and a resistor R.

Thus, the pulse signal produced by the pulse generator 19 is supplied as a frequency changing signal to the tone generator 15. The resultant frequency changed tone signals drawn out through the keyers 13 are conducted through the line 24, tone coloring filters 20, a volume control 21 and an amplifier 22 to be reproduced from a loud-speaker 23.

FIG. 3 shows a concrete circuit diagram of the one master oscillator 15 and the one frequency divider 16, the former being formed of a Hartley type oscillator 151 including a transistor TR₃ followed by a clipper including a transistor TR₆, and the latter consisting of a bistable multivibrator 161 including two emitter grounded transistor TR₄ and TR₅ cascade connected to

the transistor TR_6 respectively. In this case, the pulse signal generated by the pulse generator 19 is conducted to the base of transistor TR_3 to fluctuate its oscillation frequency.

With the instrument 10 of this invention arranged as described above, it is apparent that there are easily obtained tone signals having natural sounding characteristics closely simulating sounds of various natural musical instruments.

FIG. 4 is a block diagram of an electronic musical instrument 101 according to another embodiment of the invention.

In this embodiment, the output signal of the pulse generator 19 is not designed to be used as a direct frequency fluctuating signal, but to be used for gating the later described noise signal, thereby producing a pulsive noise signal. That is, white noise signals generated by a white noise signal source 31 are supplied through a filter 32 devised to pass only a frequency component of less than about 1,000 Hz (preferably sufficiently lower than the oscillator frequency) therethrough to a gate circuit 33 and gated by the output pulse signal from the pulse generator 19. Thereby, the oscillation frequency of each tone signal generated by the tone generator 14 is fluctuated by a pulsive noise signal e_2 thus obtained.

In FIG. 4, a numeral 34 represents switch circuits turned on or off by a player for the purpose of producing therethrough tone signals having a particular musical effect such as a sustain effect, if required.

What is claimed is:

1. An electronic musical instrument comprising: tone generators generating tone signals; tone keyers connected to said tone generators and keying said tone signals; a tone signal coupling means connected to said tone keyers and coupling the keyed tone signal to an output;

a detector means connected to said tone signal coupling means for detecting a start of said keyed tone signal; a pulse generator connected to the output of said detector means for producing a pulse signal upon detection of the start of said keyed tone signal by said detector means; and means for coupling said pulse signal to said tone generators for fluctuating the frequencies of said tone signals.

2. An electronic musical instrument according to claim 1 wherein said detector means comprises an amplitude limiter and a rectifier coupled to the output of said amplitude limiter.

3. An electronic musical instrument according to claim 1 wherein said tone generators include master oscillators generating tone signals of the notes in the highest octave and multistage frequency dividers cascade connected to each of said master oscillators for generating tone signals of the notes in the subsequent octaves.

4. An electronic musical instrument according to claim 1 wherein said pulse generator includes a one shot multivibrator.

5. An electronic musical instrument according to claim 1 which further comprises a white noise source generating white noise signals, and a filter connected to the output of said white noise source, and said means coupling said pulse signal to said tone generators comprises a gate circuit having an input thereof coupled to said filter and the output thereof coupled to said tone generators, said pulse generator being connected to another input of said gate circuit and controlling said gate circuit to gate the white noise signal to said tone generators the gated white noise signal fluctuating the frequencies of said tone signals.
